UNITED STATES PATENT OFFICE.

ADDISON T. SMITH, OF WASHINGTON, DISTRICT OF COLUMBIA.

DESIGN FOR A PAPER-WEIGHT.

SPECIFICATION forming part of Design No. 22,774, dated September 12, 1893.

Application filed July 15, 1893. Serial No. 480,660. Term of patent 3½ years.

To all whom it may concern:

Be it known that I, ADDISON T. SMITH, a citizen of the United States, residing at Washington, in the District of Columbia, have invented and produced a new and original Design for Paper-Weights, of which the following is a specification, reference being had to the accompanying drawing, in which the figure is a perspective view of my paper-weight.

5 The leading feature of my design consists of a rectangular base A in the conventionalized form of a book, the upper surface of which is embellished by a pictorial representation B of one of the "World's Fair" buildings. Upon 10 the center portion of the top of said base is

15

an oval body C representing an egg. The outer surface of the oval body is decorated with a portrait D representing a historical personage, as Columbus.

Having thus fully described my design, 20 what I claim is—

The herein described design for paper-weights, substantially as shown.

In testimony whereof I hereunto affix my signature in the presence of two witnesses.

ADDISON T. SMITH.
